UNITED STATES PATENT OFFICE.

CLARENCE G. CASHMAN, OF WAYNESBORO, PENNSYLVANIA.

REAMER-HEAD.

1,284,593.

Specification of Letters Patent. Patented Nov. 12, 1918.

Application filed January 12, 1917. Serial No. 142,007.

To all whom it may concern:

Be it known that I, CLARENCE G. CASHMAN, a citizen of the United States, residing at Waynesboro, Franklin county, and State 5 of Pennsylvania, have invented and discovered certain new and useful Improvements in Reamer-Heads, of which the following is a specification.

My said invention relates to cutter and 10 reamer heads and consists in the combinations and arrangements of elements herein-after described and particularly set forth in the accompanying claims.

The purpose of the invention is to provide 15 a cutter or reamer head of the radial adjustable blade type having means for simultaneously adjusting the several blades through a compound screwing operation; and wherein in the adjusting device acts to securely hold 20 the blades in set position.

The invention has for its further purpose 25 to provide a reamer blade adjusting device employing a minimum number of parts to the end of simplicity in construction, and wherein the adjustment of the blades may be effected in a quick, simple and easily performed operation.

The invention is shown by way of illustration in the accompanying drawing, 30 wherein,—

Figure 1 is a central longitudinal section through a reamer head, constructed in accordance with my said invention,

Fig. 2 is a transverse sectional view there- 35 of taken on the line 2—2 of Fig. 1,

Fig. 3 is a similar view taken on the line 3—3,

Fig. 4 is a detail view, partly in section of the body of the reamer head, and

Fig. 5 is a perspective view of one of the 40 reamer blades.

Referring to the construction in further detail, and wherein like reference characters designate corresponding parts, 6 represents 45 the machine spindle on which the reamer head is mounted, 7 the body of said reamer head and 8 the several reamer blades.

The reamer head consists of a cylinder 50 constructed for mounting on the machine mandrel, and is provided with a plurality of longitudinal grooves, or seats 9, arranged equidistant apart around its periphery, and adapted to receive and hold the reamer blades. Said seats or grooves are formed 55 with their bottom surfaces inclined downward from the rear to front, and the reamer

blades are formed with complementary tapered inner edges 10. Each of the grooves 9 has an inset portion 11 along a portion of its inner surface to receive the longitudinal 60 rib 12 formed on the lower edge of the blade to hold said blade against radial displacement.

The blade adjusting device consists of a screw-threaded member 13 adjustably 65 mounted in a threaded aperture formed centrally in the body 7, and constructed at its outer end with a socket 14, rectangular in cross-section, by which a tool or wrench (not shown) may be inserted for turning the 70 same. It is provided with a head 15 of relatively large diameter, and preferably formed integral therewith. Said head is provided with screw-threads, or a spiral rib 16, which engage with notches 17 formed on 75 the respective inner edges of the several blades after the manner shown in Fig. 1.

It will thus be seen that a compound screw is provided for quickly adjusting the several 80 blades, either for spreading or retracting the blades which constitute the operative head or die, and the plural engagement between the head 15 and blades 8 affords a substantial securing device to hold the several blades rigidly in set position. 85

It will be obvious to those skilled in the art that various modifications in the details of construction and arrangement of parts may be made without departing from the spirit of my invention, and that the opera- 90 tive edge of the blades, whether smooth or serrated for threading is not material, and therefore I do not wish to be limited to any particular features except as may be required by the claims. 95

Having thus fully described my said invention, what I claim as new and desire to secure by Letters Patent, is:—

1. A cutting or reaming tool comprising a body formed with radially disposed grooves, 100 blades slidably mounted in said grooves to have radial adjustment, and a compound screw engaging with said blades operable to impart radial adjustment thereto, substan- tially as set forth. 105

2. A cutting or reaming tool comprising a body formed with radially disposed grooves, 110 blades adjustably mounted in said grooves, and a member adjustably mounted in said body having screw engagement with the blades operable to adjust the latter, substan- tially as set forth.

3. A cutting or reaming tool comprising a body formed with radially disposed grooves, blades adjustably mounted in said grooves, and a member screw-threaded in said body 5 having screw engagement with the blades operable to adjust the latter, substantially as set forth.
4. A cutting or reaming tool comprising a body formed with radially disposed grooves, 10 blades slidably mounted in said grooves and constructed with notches respectively, said blades and grooves having complementary inclined portions; a member screw-threaded in said body and constructed to receive a tool, and a head mounted on said member having screw-threads engaging with the notches of the reamer blades operable to adjust said blades, substantially as set forth.
5. A cutting or reaming tool comprising a 15 body formed with radially disposed grooves having inset portions, blades slidably mounted in said grooves and provided with notches and constructed with ribs fitting in said inset portions, said blades and grooves having 20 complementary inclined portions to effect radial adjustment of the blades through longitudinal movement thereof; a member screw-threaded in said body and constructed to re-

ceive a tool, and a head mounted on said member having screw-threads engaging with 30 the notches of said blades to effect adjustment of the latter, substantially as set forth.

6. A cutting or reaming tool comprising a body formed with radially disposed grooves spaced equidistant apart around its periphery, blades slidably mounted in said grooves and provided with notches on their respective inner rear edges, said blades and grooves having complementary inclined portions to effect radial adjustment of the blades through 35 longitudinal movement thereof, a member screw-threaded in said body constructed to receive an adjusting tool, and a relatively large head mounted on said member having screw-threads engaged in the notches of said 40 blades operable to adjust the latter, substantially as set forth.

In witness whereof I have hereunto set my hand and seal at Waynesboro, Pennsylvania, this 5th day of January, A. D. nineteen hundred and seventeen.

CLARENCE G. CASHMAN. [L. S.]
